TOW BAR HITCH FOR AUTOMOBILES

Ben Goldberg, 7317 S. Crandon Ave., Chicago, Ill.

Filed Apr. 4, 1961, Ser. No. 64,616

Term of patent 7 years

(Cl. D14—6)

FIG. 1 is a perspective view of a tow bar hitch for automobiles embodying my new design;

FIG. 2 is an end elevational view thereof;

FIG. 3 is a side elevation thereof;

FIG. 4 is a top plan view, and

FIG. 5 is a bottom plan view.

The dominant features of my design reside in the portions shown in full lines.

I claim:

The ornamental design for a tow bar hitch for automobiles, as shown and described.
